Attorney, Agent, or Firm—Quarles & Brady

[57] CLAIM

The ornamental design for a handle, as shown and described.

DESCRIPTION

FIG. 1 is a perspective view taken from the top, front and left side of a handle showing our new design;

FIG. 2 is a left side elevational view thereof, the right side being the same as the left side shown;

FIG. 3 is a top plan view thereof;

FIG. 4 is a front elevational view thereof, the rear being the same as the front shown; and,

FIG. 5 is a bottom plan view thereof.

The dotted line representations of holes in FIGS. 1 and 3 are for the purpose of illustration only and form no part of the claimed design.

FIG. 1

FIG. 2

FIG. 3

FIG. 4

FIG. 5
